UNITED STATES PATENT OFFICE.

CHRISTIAN BÜRKER, JOSEF KLEE, AND JEAN KLEE, OF COLOGNE, GERMANY.

STAY OR SUPPORT WITH STEPS FOR PRODUCING CONCRETE CEILINGS.

No. 906,195

Specification of Letters Patent.

Patented Dec. 8, 1908.

Application filed April 9, 1907. Serial No. 367,171.

To all whom it may concern:

Be it known that we, CHRISTIAN BÜRKER, JOSEF KLEE, and JEAN KLEE, all subjects of the German Emperor, residing at Cologne-on-the-Rhine, Germany, have invented new and useful Improvements in Stays or Supports with Steps for Producing Concrete Ceilings, of which the following is a specification.

- 10 This invention has for its object a new ceiling support made of rammed cement, or the like, which is to be used for self-supporting ceilings instead of iron girders or wooden beams, and differs from the known ceiling supports of this kind in that respect that the size of the hollow spaces remaining between the single supports, as well as the height of the ceiling, can be regulated by using the new supports, so that these supports can be 20 equally well used with ceilings of different heights. To this end each ceiling support is provided on its lateral longitudinal faces with step-like retreats or taperings at different heights and of any form, which serve as 25 supports for closing plates or arches of a vaulted ceiling at different heights.

The invention is illustrated on the accompanying drawing.

The ceiling supports *a*, as already said, 30 form steps *b* on their vertical longitudinal faces, at different heights. The ceiling supports made of rammed cement are preferably provided on the inside with iron fillers consisting of cable wires *c* and *d* or also 35 band-iron *e*. The form of the fillers may vary, especially the band irons may, instead of being straight be of an undulated form. The band irons may also be provided with 40 holes in order to effect a closer union with the cement. Such iron fillers need not be, as shown in the drawing, in the lower half only, but may eventually also be in the upper half, or in the middle, of the joists. (See the filler *e*, indicated by dotted lines in the second 45 joist.)

The steps *b* of the supports serve to support the closing plates *f* which may be of any material, on the other arches *g*. The main object of the plates *f* is to close the 50 low spaces remaining between the supports, so that no plastering *m* of the ceiling can enter into them from the bottom. In this case the plates *f* may be fixed along the sides by cement *n*. The plates which, as shown on 55 the drawing, are used in the two hollow spaces on the left may be of terra cotta.

Each of them is provided with two upwardly directed hook-shaped projections *f*, and on the right with a prolongation *f*. The two hook-shaped projections *f* are intended to 60 rest on the lower step *b* of the supports *a*. These terra cotta plates are inserted in the manner indicated in the first hollow space by inserting the plate first from the bottom in the position indicated by dotted lines and 65 turning it down thereupon. The next terra cotta plate *f* immediately adjoins the preceding one. Below all the plates the plastering *m* is then put on. In order to make the latter adhere better, the bottom surfaces of 70 the plates *f* may be roughened or provided with recesses or grooves. But as shown in the fourth hollow space the bottom plate *f* may also be of a shape that it rests with its 75 ends on the steps *b* and that its bottom surface lies in the same plane as the lower edge of the supports *a*. In this case the plastering *m* will be little higher up than in the above described case. As shown in the third hollow space the plate *f* may also rest in the 80 position *f* on one of the next or higher steps, so that the space below can be used for installations, for instance of gas- and water-pipes and electric wires. But the plate *f* 85 may also be turned upside down and be resting on the lowest step, in which case there likewise remains a small hollow space between the plate and the plastering *m* for installations. By thus placing the plates *f* above one another hollow spaces of any size 90 may be formed between them for installations or ventilation.

The steps *b* further serve as supports for the ends of the arches *g* which may be made of any material, for instance of impregnated 95 pasteboard, terra cotta, wire gauze, sheet metal, or the like. According to the height of the ceiling to be produced the arch may be placed on different steps, for instance in the drawing it is placed between the first 100 and second joist on a lower step than between the following supports, so that also the floor *h* is on a lower level. Upon the arches *g* the concrete *i* is rammed down. The step form of the supports favors the 105 sticking of the concrete. In order to still increase the sticking of the same on the supports, the upper surfaces of the same may, as shown in the drawing on the fourth support, be provided with recesses *k*. But 110 as shown on the third support, at the upper end of the same, an additional step *l* may

quite as well be provided, which eventually may also serve to place the arch on a still higher level.

Between the fourth and fifth support instead of the arch g a plate f_3 has been put, upon which the concrete is then rammed. In this way the plates f can serve as closures at the bottom as well as at the top.

Of course the form of the steps and the supports may vary, and likewise the number of steps on each support.

What we claim as our invention and desire to secure by United States Letters Patent is:—

15 In a ceiling, the combination with the base

or facing, of cross pieces suitably spaced and having each on opposite sides a plurality of steps or shoulders at different elevations, and supporting members for bridging said spaces having ends adapted to rest on said shoulders, substantially as described.

In testimony whereof we have signed our names to this specification in the presence of two subscribing witnesses.

CHRISTIAN BURKER.

JOSEF KLEE.

JEAN KLEE.
